UNITED STATES PATENT OFFICE.

EDWARD WESTON, OF NEWARK, NEW JERSEY, ASSIGNOR TO THE UNITED STATES ELECTRIC LIGHTING COMPANY, OF NEW YORK, N. Y.

SAFETY DEVICE FOR ELECTRIC CIRCUITS.

SPECIFICATION forming part of Letters Patent No. 259,616, dated June 13, 1882.

Application filed January 5, 1882. (No model.)

To all whom it may concern:

Be it known that I, EDWARD WESTON, a subject of the Queen of Great Britain, and a resident of Newark, in the county of Essex and State of New Jersey, have invented certain new and useful Improvements in Safety Devices for Electric Circuits, of which the following is a specification, reference being had to the drawings accompanying and forming a part of the same.

The subject of my present invention is a safety device for use in electric circuits or branches thereof, with a view of preventing any abnormal flow of current therein or any accident or injury that might result from such flow.

The invention consists broadly in the combination, with an electric circuit, of a short wire strip or other equivalent conducting medium of higher relative resistance than the conductors of the circuit with which it is connected, devices constructed with a normal tendency to interrupt the continuity of the circuit, and a fusible substance surrounded by or 25 in close proximity to the resistance-wire and arranged to maintain the interrupting device in contact, but which allows the same to separate when the resistance-wire becomes heated.

In the accompanying drawings, Figure 1 is a plan view of my improved safety device; Fig. 2, a side elevation of the same, and Fig. 3 a partly-sectional view of a modification.

A is a small slab or base of insulating material—light wood, for instance; B B', binding-posts for connection with the ends of the line-wires.

C C' are short standards, clamped to base A. To one—as C—a light spring, e, is attached, which has a normal tendency to assume the 40 position indicated in dotted lines.

To the other standard, C', spring e' is fixed. This spring should be under greater tension when the apparatus is set, and for this purpose, when freed, should assume the position indicated by dotted lines.

D is a rest or standard of any description.

E is a stick of paraffine, shellac, or some other easily-fusible substance, and of such length that it may be held in position between 50 the rest D and a suitable socket or spring, e.

F is a fine platinum, copper, or other wire, which will readily permit the passage of a normal current, but which becomes heated by any marked increase in its flow. It is coiled about the paraffine rod, as shown, and connects the binding-post B with standard C.

A connecting-wire, G, is used to complete the circuit from standard C' to post B'.

The operation is as follows: The stick of fusible substance inclosed in the coil F is set 60 in position between spring e and standard D. Spring e' is brought up over the end of spring e, by which it is retained under tension. In this condition the apparatus permits the flow of current necessary to the requirements of 65 the circuit in which it is included. Should the current increase for any reason beyond the normal limits the coil F becomes heated and softens the stick of fusible material, which, being under compression, bends sufficiently to allow 70 the spring e' to slip off from the end of spring e with a snap, the rapidity with which the contact is broken preventing the formation of any injurious sparks.

In order that the material composing the 75 stick E may be rendered more sensitive to the action of heat I make it of wax, shellac, or similar substance, and a small quantity of powdered metal, preferably copper, the two being thoroughly mixed. By this means its heat-conducting properties are increased.

It is evident that the above is one only of a great number of ways in which the invention may be carried into effect. For this reason Fig. 3 is given in illustration of a slightly-modified plan. Here, the other parts remaining the same, a slightly-conical plug or button of highly-fusible material, H, in a copper shell, K, of corresponding shape, is substituted for the rod or stick E. The wire F is carried around 85 the shell K, though insulated from it, so that the heat generated by an abnormal flow of current is imparted to the shell. By this means the surface of the fusible plug is softened and the plug itself driven through the shell by 90 springs e and e'. The wires F and G are carried around the shell K, though insulated from it, so that the heat generated by an abnormal flow of current is imparted to the shell. By this means the surface of the fusible plug is softened and the plug itself driven through the shell by 95 springs e and e'.

The sticks or plugs of fusible material are easily replaced in the event of their being melted, so that the above forms a very desirable device, not only from the slight expense 100

which its construction involves, but from the absolute safety from accident or injury which its use insures.

Having now described my invention and the best manner of which I am at present aware in which the same is or may be carried into effect, what I claim is—

1. The combination, with an electric circuit, of a wire or similar conducting medium of higher relative resistance than the conductors with which it is connected, a circuit-interrupter, and a mass of fusible material surrounded by or in proximity to the wire of high resistance, and arranged to maintain the continuity of the circuit through the interrupter until softened by heat.

2. In a safety device for electric circuits, the combination, with a circuit-interrupter, of a

mass of highly-fusible material for preventing the same from acting, and a resistance-wire 20 included in the circuit with the interrupter and in proximity to the fusible material, substantially as set forth.

3. In a safety device for electric circuits, the combination of springs *c c'*, a mass of fusible 25 material for maintaining the same in contact, and a resistance-wire surrounding the fusible material, for the purpose set forth.

4. The rod *E*, or its equivalent, composed of a non-conducting substance, which softens at 30 a low temperature, and powdered metal for rendering the same a better conductor of heat.

EDWARD WESTON.
